BRIQUETTING PRESS

Paul E. Flowers, Shaker Heights, Ohio, assignor to
 The Hydraulic Development Corporation, Inc.,
 Wilmington, Del., a corporation of Delaware

Application February 23, 1942, Serial No. 432,027

11 Claims. (Cl. 18—16)

This invention relates to presses and, in particular, to briquetting presses.

Briquetting presses as heretofore known are relatively complicated in structure and, therefore, entail relatively high cost of production and assembly. In particular, these known presses require special measuring means, separate ejector means, and separate motor means for actuating said ejector means and said measuring means, and special timing means for assuring the proper sequence of the operation of said various means.

It is, therefore, an object of this invention to provide an improved briquetting press which will be materially simplified over presses of this type as heretofore known and which will be simple in construction, assembly and operation.

It is another object of this invention to provide a briquetting press comprising a press plunger which will serve the dual purpose of compressing and meting out the quantity of material to be compressed during a pressing stroke.

It is still another object to provide a briquetting press in which the meting out of material to be compressed and the compression of said material is effected by the press plunger during one and the same stroke thereof.

A further object of the invention consists in the provision of a briquetting press which comprises an element, adapted, in cooperation with the press plunger, to serve the dual purpose of meting out the material to be compressed during a pressing stroke of said plunger and to eject the compressed material following the completion of said pressing stroke.

A still further object of the invention consists in the provision of a press as set forth in the preceding paragraph, in which the movement of the press plunger times the operation of the ejector means for the compressed material.

It is another object to provide a briquetting press which comprises a charging box adapted to be reciprocated for facilitating the ejection of the compressed material.

Still another object of the invention consists in the provision of a briquetting press in which gravity may be taken advantage of for feeding the material to be compressed and for facilitating the ejection of the compressed material.

These and other objects and advantages of the invention will appear more clearly from the following specification in connection with the accompanying drawings, in which:

Figure 1 is a top view of the press according to the invention.

Figures 2, 3, 4, 5 and 6 show sections through

the press and illustrate various phases of a working cycle.

Figure 7 is an enlarged section along the line 1—7 of Figure 5.

Figure 8 diagrammatically illustrates the hydraulic circuit of the press shown in Figures 1 to 7.

General arrangement

The briquetting press according to the invention substantially comprises a charging box which receives the material to be compressed and has two openings adapted to be closed by a press plunger and an ejector operatively connected with said press plunger.

The press plunger is adapted to enter the charging box and, in cooperation with said ejector, to feed the material between said plunger and said ejector into a forming cylinder, in which said material is compressed as soon as the ejector reaches the end of its stroke, while the press plunger continues its movement toward said ejector.

At the end of the pressing stroke, the movement of the press plunger is reversed, so that the latter moves away from the ejector and, after having reached a predetermined spaced position relative to said ejector, picks up the latter and causes it to eject the compressed material.

To facilitate the ejection of the compressed material, the charging box is moved away from the forming cylinder when the press plunger is on its retraction stroke.

Structural arrangement

Referring now to the drawings in detail, the briquetting press shown therein comprises substantially a main cylinder 10 having reciprocably mounted therein a ram 11 with a main area 12 and a booster cylinder 13. Mounted in the booster cylinder 13 is a piston 14 with a piston rod 15 threadedly connected to a sleeve 16 which, in its turn, is rigidly connected to the main cylinder 10.

The rod 15 has a longitudinal bore 17 therethrough adapted to effect fluid communication between the port 18 at one end of the main cylinder 10 and the bottom end of the booster cylinder 13.

Connected to the ram 11 in any convenient manner, for instance by means of a split ring 19 and screws 20, is a platen 21 carrying a press plunger 22. The platen 21 is slideable on and guided by strain rods 23 interconnecting the main cylinder 10 and the base member 24. The base member 24 comprises a forming cylinder 25 hav-

ing & its right end annular grooves 26 connecting an outlet passage 27 and an inlet passage 28, which latter is adapted to admit compressed air for cleaning the forming cylinder 25 of undesired particles of the material previously compressed which remained in the cylinder.

The inlet passage 28 is connected through a conduit 29 with a two-way valve 30 having a valve member 31 adapted to be actuated so as to establish fluid communication between the conduits 29 and 32 when the bell crank lever 33 is shifted in clockwise direction. The conduit 32 is connected with a container 34 comprising compressed air.

The forming cylinder 25 is provided with a lining 35 and a hardened end 36. Reciprocably mounted in the forming cylinder 25 is a piston 37 connected to a piston rod 38 which passes through a bore 39 in the base member 24 and has adjustably connected thereto a collar 40. The collar 40 is adapted to engage a yoke 41 which is connected by means of connecting rods 42 with the platen 21 so that the yoke 41 moves in unison with the platen 21.

The yoke 41 carries an arm 43 which moves the bell crank lever 33 in anti-clockwise direction when the yoke 41 moves toward the right, whereas the arm 43 moves the bell crank lever 33 in clockwise direction so as to establish fluid communication between the conduits 29 and 32 when the yoke 41 moves toward the left. The piston rod 38 extends through the yoke 41 and carries an adjustable collar 44 adjacent its outer end. The collar 44 engages one end of a spring 45, the other end of which abuts the yoke 41. The spring 45 continuously urges the yoke 41 into engagement with the collar 40.

The base member 24 supports a hopper 46 adapted to receive material to be briquetted and to feed this material into a charging box 47 which is reciprocable and guided by the strain rods 23 by means of guiding arms 48. The charging box 47 has in one side wall thereof adjacent its bottom 49 a bore 50 into which extends the press plunger 22 so that the latter closes the said bore. The opposite wall of the charging box 47 is also provided with a bore 51 of the same diameter as the bore 50, so that the press plunger 22 may also pass through the bore 51. When the press plunger 22 is retracted from the bore 51, the latter may be closed by the piston 37. To prevent material to be briquetted from undesirably entering the interior of the machine, the hopper 46 is provided with an apron 52, while the charging box 47 is provided with an apron 53.

Connected with the charging box 47 is a plurality of cylinder piston assemblies, generally designated 54 (only one shown in the drawings). The cylinder piston assembly 54 comprises a cylinder 55 connected to the main cylinder 10 and having reciprocably mounted therein a piston 56 which, in its turn, is connected by a piston rod 57 with the charging box 47.

The cylinder 55 has connected thereto a conduit 58 leading to a container (not shown in the drawings) filled with compressed fluid, such as air. The cylinder piston assembly 54 serves the purpose of returning the charging box 47 to its position shown in Figure 2 from the position shown in Figure 6.

The charging box 47 has connected thereto in any convenient manner, for instance by screws 59, an abutment 60 for cooperation with a cam 61 pivotally connected by means of pivot 62 with an arm 63 which, in its turn, is connected to the platen 21. The cam 61 carries a roller 64 for co-

operation with the stationary cam 65 so that when the roller 64 moves up the cam 65, the cam 61 rotates in anti-clockwise direction and abuts the abutment 60.

5 The hydraulic circuit for the machine shown in Figures 1 to 7 is illustrated in Figure 8, from which it will be noted that the port 18 of the main cylinder 10 is connected by a conduit 66 to an admission valve 67 which, in its turn, is connected to one side of a reversible variable delivery pump 68, the other side of which communicates through a conduit 69 with a port 70 in the main cylinder 10. The port 70 communicates with the retraction side of the ram 11. The admission valve 67 does not form a part of the present invention and for a more detailed description thereof reference may be had to U. S. Patent 2,086,295 to Ernst.

20 The admission valve 67 operates so that it normally allows fluid from the pump 68 to flow through conduit 66 into the port 18 and when a predetermined pressure is established in the conduit 66, the valve 67 opens a connection between the conduit 66 and a conduit 71 connected to the bell conduit 72, one end of which leads to the main area 12 of the ram 11, while the other end comprises a check valve 73 and leads to a fluid storage tank 74.

25 The tank 74 communicates through a conduit 75 with a shuttle valve 76 which may be of any standard design and which, in its turn, communicates through conduit 77 with the conduit 69 and through conduit 78 with the conduit 66.

30 Communicating with the conduit 72 is a conduit 79 leading to a dash pot, generally designated 80, which comprises a cylinder 81 and a piston 82. The piston 82 has connected thereto a rod 83 which is connected by a link 84 with a link 85 forming a part of the snap switch, generally designated 86.

35 When the snap switch 86 is in the position shown in Figure 8, the contacts 87 and 88 engage each other. If, on the other hand, the piston 82 has moved to its uppermost position, it has actuated the switch 86 so as to disengage the contacts 87 and 88. The piston 82 is urged into its lowermost position by a spring 89.

40 The cylinder 81 is connected by means of conduit 90 with a choker check valve arrangement 91 which throttles the fluid, such as air, expelled by the piston 82 from the cylinder 81 when the piston 82 moves upwardly, while allowing unrestricted supply of fluid into the cylinder 81 when the piston 82 moves downwardly.

45 The contact 87 is connected with the main supply line 92, while the contact 88 is connected with the main supply line 93 comprising a starter switch 94 which, when closed, establishes connection between the main supply line 93 and the solenoid 95. Energization of the solenoid 95 moves the variable delivery pump 68 into full delivery forward stroke position, while the spring 96 is adapted to move the pump 68 into full delivery retraction stroke position when the solenoid 95 is deenergized. To allow fluid to escape from the main area to the tank 74 during the retraction stroke of the ram 11, the check valve 73 is bypassed by a conduit 98 comprising a pilot operated valve 100, which establishes fluid connection around the check valve 73 when a predetermined pressure in the line 69 is conveyed to the valve 100 through the pilot line 101.

Operation

50 It may be assumed that the briquetting press

according to the invention occupies the position shown in Figure 2, while the elements in the circuit occupy the position shown in Figure 8; it may furthermore be assumed that the hopper and charging box are filled with material to be compressed.

To start a working cycle, the operator closes the starter switch 94, thereby energizing the solenoid 95. Energization of the solenoid 95 shifts the pump 68 into full delivery forward stroke position, and assuming that the pump was previously started, pressure fluid is now delivered by the pump 68 through conduit 66, port 18 and bore 17 into the booster cylinder 13. As a result thereof, the ram 11 moves toward the right, thereby also moving the platen 21 and press plunger 22 toward the right. This phase is illustrated in Figure 3. During this rightward movement, the cam 61 merely slides beneath the abutment 60 but does not affect the operation of any parts. The suction caused by the rightward movement of the ram 11 in the cylinder 10 causes fluid to flow from the tank 74 through conduit 72 to the main ram area 12. Rightward movement of the press plunger 22 causes the latter to enter the charging box 47 and to move the material in front of the plunger 22 toward the right into the forming cylinder 25.

The piston 37 recedes accordingly, due to the fact that the yoke 41 is directly connected to the platen 21 and, thereby, to the press plunger 22, so that the rightward movement of the press plunger 22 causes the yoke 41 to move the rod 38 through the intervention of the spring 45. In other words, during the transfer of the material from the charging box 47 into the forming cylinder 25, the press plunger 22 and the piston 37 remain spaced at a predetermined substantially constant distance. When, during this material transferring operation, the piston 37 has reached its right hand end position, it comes to a halt, while the plunger 22 continues its rightward movement and now performs the actual pressing operation.

As soon as the press plunger 22 encounters a predetermined resistance, or, in other words, as soon as a predetermined fluid pressure has built up in the booster cylinder, this pressure is conveyed through conduit 66 to the admission valve 67 so as to open the latter, and fluid pressure from the pump 68 now passes through the conduits 71 and 72 to the main ram area 12, thereby increasing the actual forming pressure. The pressure in line 42 closes the check valve 73. During the actual pressing operation, which is shown in Figure 4, the yoke 41 compresses the spring 45. The pressure in conduit 72 is also conveyed through conduit 78 to the piston 82.

When a predetermined pressure has built up in the conduit 72, the piston 82, by means of the rod 83 and links 84 and 85, shifts the snap switch 86 so as to open the latter. This results in interruption of the energizing circuit for the solenoid 95 so that the spring 96 moves the pump 68 into full delivery retraction stroke position.

Pressure fluid from the pump 68 now flows through conduit 69 to the port 70 and starts to retract the ram 11, while the fluid expelled from the main ram area 12 and from the booster cylinder 13 passes through conduits 66 and 72 to the pump 68 and the tank 74 respectively.

The retraction movement of the ram 11 results in a leftward movement of the press plunger 22. However, since the yoke 41 was spaced from the collar 40 at the end of the actual pressing stroke,

the press plunger 22 moves toward the right by a predetermined distance before the yoke 41 again engages the collar 40. Consequently, the press plunger 22 recedes with regard to the piston 37 by a distance which is greater than the length of the compressed material in the forming cylinder 25 so that the compressed material can be ejected from the forming cylinder without difficulty.

When the yoke 41, during the leftward movement of the plunger 22, again engages the collar 40, or, about this time, the cam roller 64 of the cam 61 has moved up on the cam 65 so as to bring the cam 61 into engagement with the abutment 60. Further leftward movement of the press plunger 22 and, thereby, the platen 21, causes the cam 61 to pick up the charging box 47 through the intervention of the abutment 60, which charging box now moves leftwardly in unison with the plunger 22, thereby also spacing the charging box 47 from the adjacent end of the forming cylinder 25. As soon as the yoke 41 engages the collar 40, it picks up the said collar and moves the piston 37, through the intervention of the rod 38, likewise toward the left so that the piston 37 acts as an ejector and ejects the compressed material in front thereof. When the ejector piston 37 approaches the end of its leftward movement, the compressed material drops by gravity into a collecting container or conveyor, not shown in the drawings. This phase of the operation is illustrated in Figure 5.

When the piston 37 approaches the end of its leftward stroke, the arm 43 engages the bell crank lever 33 so as to cause the latter to move in clockwise direction and, by means of the valve member 31, to establish fluid connection between the container 34 and the conduit 28 so that compressed air blows through the passage 28 into the forming cylinder 25 and blows undesired particles therefrom through the outlet passage 27.

The press ram 11 and, therefore, also the press platen 21 continue their leftward movement after the compressed material has been ejected from the forming cylinder 25. During this last portion 45 of the leftward movement of the ram 11, the cam roller 64 of the cam 61 leaves the stationary cam 65 and thereby, due to gravity, also leaves the abutment 60. As a result thereof, the compressed air in the cylinders 65 moves the pistons 56 toward the right, thereby returning the charging box 47 to Figure 4 position. It will be noted that, during the leftward movement of the charging box 47 no material from the hopper 46 can fall into the machine because, during this movement, the apron 53 forms a bottom for the hopper 46.

When the press ram 11 has returned to Figure 2 position, the other parts of the machine have likewise reached Figure 2 position, and a predetermined pressure builds up in conduit 69 which is conveyed through conduit 91 to a servomotor 92, which shifts the pump 68 to substantially neutral or no delivery position. The machine is now ready for a new cycle.

It will be appreciated from the foregoing description that by adjusting the choke 91a of the choker check valve arrangement 91, the time of opening the snap switch 86, and, thereby, the time for the reversal of the ram 11 may be varied.

While the press illustrated in the drawings is shown as a horizontal briquetting press, and while such horizontal press facilitates the feeding of material to be compressed and the discharge of the compressed material from the forming cylinder over vertical briquetting presses, it is to be

understood that the main features of the present invention are not limited to horizontal briquetting presses, but may, for instance, be used in connection with vertically arranged briquetting presses.

It should furthermore be noted that, if desired, the cylinder 55 may be replaced by a spring, or the movement of the charging box 47 toward the left may be effected by a spring or cylinder piston assembly instead of by the cam arrangement 61, 65 as shown in the drawings. Furthermore, the spring 45 may also be replaced by a fluid operable cylinder piston assembly.

It will be understood that I desire to comprehend within my invention such modifications as come within the scope of the claims and the invention.

Having thus fully described my invention, what I claim as new and desire to secure by Letters Patent is:

1. In a briquetting press, a substantially horizontally arranged press cylinder, a substantially vertically arranged container for receiving material to be compressed in said press cylinder, and a pair of pistons operable to close said container at the lower end thereof movable in one direction for transferring a portion of the material in said container from the latter into said press cylinder and subsequently to cause compression of said material in said cylinder, means interconnecting said pistons and operable to maintain the same in a predetermined spaced relationship during said material transferring movement, said pistons being movable in the opposite direction for ejecting the compressed material from said press cylinder and a fluid operable plunger operable to reciprocate both pistons.

2. In a briquetting press, a container adapted to receive material to be compressed, a press cylinder, a first plunger positioned to extend into said container, a second plunger also positioned to extend into said container, mechanical means interconnecting said first and second plungers, yielding means associated with said mechanical means for continuously urging said plungers into a predetermined relative position and for permitting relative movement between said plungers, means for moving said plungers in unison in one direction to cause the same to transfer a predetermined quantity of material from said container into said cylinder and to move said first plunger while said second plunger is stationary, means to hold said second plunger stationary while said first plunger continues its movement in said direction to compress said material within said cylinder and between the plungers.

3. In a briquetting press, a press cylinder, a container for receiving material to be compressed, said container comprising a first opening and a second opening, said openings having the same diameter and being arranged in alignment with each other, a first plunger closing said first opening in one of its positions, a second plunger aligned with and spaced from said first plunger and selectively closing said first and said second openings and passing therethrough in one of its positions, means for positively limiting said spacing to a predetermined maximum distance, means interconnecting said plungers so constructed as to permit said plungers to move toward each other, means for moving said plungers in unison for transferring a measured quantity of material between said plungers from said container into said press cylinder, means operable after said material has been transferred into said cylinder for

halting said first plunger and while said second plunger continues to move thereby to cause compression of the material in said cylinder between said two plungers.

4. In a briquetting press, a container for receiving material to be compressed, a press cylinder, a first plunger, a second plunger spaced from said first plunger, said plungers being positioned on opposite sides of said container and positioned to extend thereinto, means for positively limiting said spacing to a predetermined maximum amount, motor means for moving said plungers in unison in a first direction for transferring a predetermined quantity of material from said container into said press cylinder, means for arresting said second plunger at the end of said material transferring action while continuing further movement of said first plunger in said first direction, to cause said first plunger to compress the material between said first and second plungers, means associated with said motor means for retracting said first plunger to restore said predetermined maximum spacing of said first plunger from said second plunger, means associated with said motor means for thereafter causing said motor means to move said plungers in unison to eject the compressed material from the press cylinder, and means for retaining said second plunger in said arrested position while said first plunger is being retracted to restore said maximum spacing.

5. In a briquetting press, a press cylinder, a movable container having plunger receiving apertures for receiving material to be compressed in said press cylinder, and a pair of plungers arranged in spaced relationship and movable through said apertures in a first direction for transferring a predetermined fraction of the material in said container from the latter into said cylinder, means for maintaining said spaced relationship of said plungers until said material has been transferred into said cylinder, said means being constructed and arranged to permit said plungers to move relatively to one another thereby to compress said material therebetween, means to cause the container to become spaced from the cylinder in a second direction, and a fluid operable motor for reciprocating said pair of plungers.

6. In a briquetting press, a substantially horizontal press cylinder, a movable container for receiving material to be compressed in said press cylinder, spaced plungers movable in a first direction for transferring material from said container into said press cylinder and subsequently causing compression of said material in said cylinder, said plungers also being movable in a second direction for ejecting the material from said press cylinder, means interconnecting said plungers and operable to maintain the same in a predetermined maximum spaced relationship during said material transferring movement and for thereafter permitting relative movement of said plungers toward one another during said material compressing movement, a double acting fluid operable plunger for reciprocating said plungers first named, means for moving said container away from said cylinder prior to the final ejection of the material from said cylinder, and means operable subsequently to the final ejection of said material from said cylinder for returning said container to its initial position.

7. A briquetting press including a charging box for receiving disintegrated material having a cylinder as a part thereof; a compression chamber;

means for reciprocating said charging box into and out of connection with said compression chamber; two openings in opposite side walls in said charging box, said openings being of equal size and in axial alignment with each other, said cylinder, and with said compression chamber; a press plunger operable in said cylinder; an ejector; said press plunger and said ejector closing one of said two openings selectively; means for moving said charging box relatively to said compression chamber for feeding a predetermined quantity of disintegrated material into said cylinder from said charging box upon movement thereof toward said compression chamber; means for moving said press plunger through said charging box to transfer the material in said cylinder into said compression chamber to compress the material, means for maintaining said press plunger and said ejector in predetermined spaced relationship during the feeding operation of said compression chamber; and means for arresting said ejector during compression of the material by said press plunger.

8. A briquetting press including a charging box for receiving disintegrated material having a cylinder as a part thereof; a compression chamber; means for reciprocating said charging box into and out of connection with said compression chamber; two openings in opposite side walls in said charging box, said openings being of equal size and in axial alignment with each other, said cylinder, and with said compression chamber; a press plunger operable in said cylinder; an ejector; said press plunger and said ejector closing one of said two openings selectively; means for moving said charging box relatively to said compression chamber for feeding a predetermined quantity of disintegrated material into said cylinder from said charging box upon movement thereof toward said compression chamber; means for moving said press plunger through said charging box to transfer the material in said cylinder into said compression chamber to compress the material, means for maintaining said press plunger and said ejector in predetermined spaced relationship during the feeding operation of said compression chamber; and means for arresting said ejector during compression of the material by said press plunger, and means for automatically spacing the charging box from the compression chamber by a predetermined distance in order to facilitate the ejection of the briquette formed.

9. A briquetting press including a charging box for receiving disintegrated material having a cylinder as a part thereof; a compression chamber; means for reciprocating said charging box into and out of connection with said compression chamber; two openings in opposite side walls in said charging box, said openings being of equal size and in axial alignment with each other, said cylinder, and with said compression chamber; a press plunger operable in said cylinder; an ejector; said press plunger and said ejector closing one of said two openings selectively; means for moving said charging box relatively to said compression chamber for feeding a predetermined quantity of disintegrated material into said cylinder from said charging box upon movement thereof toward said compression chamber; means for

10 moving said press plunger through said charging box to transfer the material in said cylinder into said compression chamber to compress the material, means for maintaining said press plunger and said ejector in predetermined spaced relationship during the feeding operation of said compression chamber; and means for arresting said ejector during compression of the material by said press plunger, and a lost motion means connecting said ejector with said press plunger.

10. A briquetting press including a charging box for receiving disintegrated material having a cylinder as a part thereof; a compression chamber; means for reciprocating said charging box into and out of connection with said compression chamber; two openings in opposite side walls in said charging box, said openings being of equal size and in axial alignment with each other, said cylinder, and with said compression chamber; a press plunger operable in said cylinder; an ejector; said press plunger and said ejector closing one of said two openings selectively; means for moving said charging box relatively to said compression chamber for feeding a predetermined quantity of disintegrated material into said cylinder from said charging box upon movement thereof toward said compression chamber; means for moving said press plunger through said charging box to transfer the material in said cylinder into said compression chamber to compress the material, means for maintaining said press plunger and said ejector in predetermined spaced relationship during the feeding operation of said compression chamber; and means for arresting said ejector during compression of the material by said press plunger, a lost motion means connecting said ejector with said press plunger, said means for moving the press plunger comprising a fluid operable cylinder-piston-assembly and a hydraulic motor connected therewith, for reciprocating the press plunger.

11. A briquetting press including a charging box for receiving disintegrated material having a cylinder as a part thereof; a compression chamber; means for reciprocating said charging box into and out of connection with said compression chamber; two openings in opposite side walls in said charging box, said openings being of equal size and in axial alignment with each other, said cylinder, and with said compression chamber; a press plunger operable in said cylinder; an ejector; said press plunger and said ejector closing one of said two openings selectively; means for moving said charging box relatively to said compression chamber for feeding a predetermined quantity of disintegrated material into said cylinder from said charging box upon movement thereof toward said compression chamber; means for moving said press plunger through said charging box to transfer the material in said cylinder into said compression chamber to compress the material, means for maintaining said press plunger and said ejector in predetermined spaced relationship during the feeding operation of said compression chamber; and means for arresting said ejector during compression of the material by said press plunger, and means for passing compressed fluid through the compression chamber during the ejecting operation of the ejector.

PAUL E. FLOWERS.
